(21) Appl. No.: **29/591,401**

The ornamental design for a recessed lighting fixture with a flexible driver assembly, as shown and described.

(22) Filed: **Jan. 19, 2017**

DESCRIPTION

(51) **LOC (12) Cl. 26-05**

FIG. 1 is a perspective view of the front side of a recessed lighting fixture with a flexible driver assembly where the enclosure box is transparent;

(52) **U.S. Cl. USPC** **D26/74**

FIG. 2 illustrates a top-perspective view of the recessed lighting fixture with the enclosure box shown as being transparent.

(58) **Field of Classification Search**

FIG. 3 illustrates a bottom-up view of the recessed lighting fixture with the enclosure box shown as being transparent.

USPC D26/74, 72, 75, 76, 77, 78, 85, 88, 89,
D26/118, 138, 141; 362/364, 365, 373,
362/145, 146, 147, 148, 150, 153, 153.1,
362/294, 296.01, 296.07, 296.08

FIG. 4 illustrates a top-down view of the recessed lighting fixture with the enclosure box shown as being transparent.

See application file for complete search history.

FIG. 5 illustrates a first side view of the recessed lighting fixture with the enclosure box shown as being transparent; and,

FIG. 6 illustrates a second side view of the recessed lighting fixture with the enclosure box shown as being transparent.

References Cited

The broken lines shown in the drawings represent portions of the recessed lighting fixture with a flexible driver assembly that form no part of the claimed design.
